CLAIM

We claim the ornamental design for the utility vehicle, as shown and described.

DESCRIPTION

FIG. 1 is a perspective view of the utility vehicle showing our new design;

FIG. 2 is a left side elevation view;

FIG. 3 is a right side elevation view;

FIG. 4 is a top plan view;

FIG. 5 is a bottom plan view;

FIG. 6 is a front elevation view; and,

FIG. 7 is a rear elevation view.

In the drawings, the broken lines depict unclaimed subject matter only and form no part of the claimed design.
